UNITED STATES PATENT OFFICE

ROSETTA RICH STRASSER, OF NEW YORK, N. Y.

SMOKER'S FINGER GLOVE

Application filed July 25, 1931. Serial No. 553,112.

This invention relates to new and useful improvements in a smoker's glove.

In recent years it has been the custom for ladies to smoke. They experience annoyance in that the fingers with which they hold the cigarettes become discolored.

It is an object of this invention to construct a smoker's finger glove which is characterized by the ability of engaging upon a pair of adjacent fingers with which a person holds a cigarette for the purpose of shielding the fingers against discoloration and against tobacco odors.

It is another object of this invention to construct a smoker's finger glove which is characterized by sheet material in the form of fingers for covering adjacent fingers of one's hand and joined together at the bottom in an integral unit.

A still further object of this invention is to arrange means on the bottom edge of the glove for holding it tightly upon one's hand.

This invention has a still further object, which consists in cutting off the tips of the gloves so that the fingers may be exposed and thus prevent annoyance.

Another one of the objects of this invention is the construction of a smoker's finger glove which is characterized by the provision of one or more pieces of reinforcements upon the fingers thereof and adapted to better hold cigarettes.

Furthermore, as another object, it is proposed to provide a means whereby the reinforcements mentioned in the previous paragraph may be adjusted.

A still further object of this invention is the construction of a smoker's glove of the class mentioned which is of simple, durable construction, dependable in use and efficient in action, and which can be manufactured and sold at a reasonable cost.

For further comprehension of the invention, and of the objects and advantages thereof, reference will be had to the appended claims in which the various novel features of the invention are more particularly set forth.

In the accompanying drawing forming a material part of this disclosure:—

Fig. 1 is a perspective view of a smoker's finger glove constructed according to this invention.

Fig. 2 is a similar view but illustrating a modified form of glove, a portion thereof being shown in section.

Fig. 3 is another view similar to Fig. 1 but illustrating a still further modification.

Fig. 4 is another view similar to Fig. 1 but illustrating a still further modification.

Fig. 5 is a sectional view taken on the line 5—5 of Fig. 4.

Fig. 6 is a fragmentary sectional view taken on the line 6—6 of Fig. 5.

Fig. 7 is another view similar to Fig. 1 but illustrating a still further modification.

Fig. 8 is a sectional view taken on the line 8—8 of Fig. 7.

Fig. 9 is a fragmentary sectional view taken on the line 9—9 of Fig. 7.

The smoker's finger glove, according to this invention, comprises sheet material in the form of fingers 10 and 11 for covering adjacent fingers on one's hand and joined together at the bottom 12 in an integral unit. A bulged edge 13 is formed along the bottom edge of the joined fingers for the purpose of providing tension to hold the glove upon one's hand. Dot and dash lines 14 indicate one's hand with the glove applied on the forefinger and the finger adjacent. A cigarette, indicated by dot and dash lines 15, is shown between the fingers of the glove.

In Fig. 2 a modification of the invention has been disclosed in which the tips of the fingers are cut away so as to provide openings 15 through which the finger tips of one's hand may project. In other respects this form of the invention is similar to the preferred form, corresponding parts being indicated by similar reference numerals.

In Fig. 3 a still further modification of the invention has been disclosed in which the bottom edge of the joined fingers is finished with a rough edge 16. In this form of the invention and in the forms illustrated in Figs. 1 and 2, the material may be of any desirable color and quality. Preferably, it should be of such material that can be turned completely out so that both sides may be used.

An ideal material for the purpose would be thin rubber so that it may engage against one's fingers conveniently.

In Figs. 4 and 6 inclusive, another modification of the invention has been disclosed in which reinforcement pieces 17 are shown mounted upon the fingers for the purpose of better holding a cigarette. These reinforcement pieces are arranged so as to be capable of assuming various positions along the finger lengths. They are in the form of wide portions having straight recesses 18 for acting against the sides of a cigarette and backward extending prongs 19 for encircling the fingers. These prongs have a large degree of resiliency so that they tend to collapse the fingers.

A rigid ring 20 is located within each of the fingers and is formed with peripheral projecting ridges 21 capable of forcing the material of the glove into corresponding grooves 22 formed in the inner face of the portions 18 and 19 of the reinforcements. The location of the reinforcements may be changed by manually prying the prongs 19 slightly open, changing the location of the finger ring 20 in its new location. The ridges 21 and the grooves 22 serve to tightly clamp the reinforcements on the fingers.

In Figs. 7 to 9 inclusive another modification of the invention has been disclosed in which reinforcements 23 are provided which are of longitudinal shape. These reinforcements are also provided with transverse grooves 18 to accommodate the curvature of the sides of a cigarette. The reinforcements 23 have projecting prongs 24 which encircle the fingers of the glove. A ring 25 is located within each of the fingers and is formed with a groove 26 for accommodating the prongs 24.

The operation of the article consists in its location upon adjacent fingers which are to hold a cigarette. After smoking is completed it may be taken off and placed in one's handbag. In the form shown in Fig. 2, the finger nails may be used to lift up articles even though the glove is in place upon one's hand.

In the form illustrated in Figs. 4 to 9 inclusive, the reinforcement members may be adjusted to various locations upon the fingers so that a cigarette may be supported according to the best tastes of the smoker.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a finger glove hav-

ing two fingers for covering adjacent fingers on one's hand, cigarette holding pieces mounted upon said fingers and having opposite curved recesses for engaging against the opposite sides of a cigarette, and means for adjustably holding said holding pieces comprising a ring within each finger and having ridges engaging through the materials of the fingers and into grooves in said holding pieces, the holding pieces being provided with prong portions extending substantially around the fingers.

2. In combination with a finger glove having two fingers for covering adjacent fingers on one's hand, cigarette holding pieces mounted upon said fingers and having opposite curved recesses for engaging against the opposite sides of a cigarette, and means for adjustably holding said holding pieces comprising a ring within each finger and having ridges engaging through the materials of the fingers and into grooves in said holding pieces.

In testimony whereof I have affixed my signature.

ROSETTA RICH STRASSER.
